UNITED STATES PATENT OFFICE.

EDWARD F. CRANE, OF NEWARK, NEW JERSEY.

METALLIC REINFORCING STRUCTURE FOR CEMENTITIOUS BODIES.

No. 879,444.

Specification of Letters Patent.

Patented Feb. 18, 1908.

Application filed July 19, 1906. Serial No. 326,820.

To all whom it may concern:

Be it known that I, EDWARD F. CRANE, citizen of the United States, and resident of Newark, in the county of Essex and State of New Jersey, have invented certain new and useful Improvements in Metallic Reinforcing Structures for Cementitious Bodies, of which the following is a specification.

The object of my invention is to provide a metallic re-inforcing structure for cementitious bodies that will be simple in construction and highly efficient in use.

To this end, the invention consists in the novel features of construction and combinations of parts to be hereinafter described in detail and particularly pointed out in the claims.

In the accompanying drawings, which illustrate the invention, Figure 1 is a transverse sectional view of a cementitious body provided with my improved re-inforcing structure. Fig. 2 is a detail plan view of the re-inforcing structure on the line 2—2, Fig. 1. Fig. 3 is a view showing the manner of assembling the parts of the re-inforcing structure. Fig. 4 is a plan view of a locking plate forming part of the structure. Fig. 5 is a view of a modification of the invention, and Fig. 6 is an elevation of the embodiment of the invention shown in Fig. 5.

The invention includes, generally, a main re-inforcing bar, a plurality of transversely disposed shearing members or stirrups associated with said bar, and a locking-clip associated with each shearing member for securing the same to the bar.

The invention is particularly adapted for use with beams or like bodies constructed of cementitious material and is shown in this connection in the illustrated embodiment thereof. The beam illustrated is of rectangular shape in cross section and is designated 2.

The main re-inforcing bar is designated 3 and is adapted to extend lengthwise of the beam 2 near the bottom of the same. The re-inforcing bar herein illustrated is of novel construction, the same being provided with a plurality of peripheral spirally arranged ribs 3', and the shearing members associated with the bar combine with this particular construction of bar in a peculiar manner to be hereinafter referred to, which gives additional advantages over a re-inforcing bar having a plane periphery, but it will be

understood that the invention is not limited to a construction in which this particular shape of bar constitutes one of the parts. One of the shearing members associated with the bar is designated 4. It will be understood that a number of these members are spaced short distances apart throughout the length of the bar 3, are disposed transversely of the same, and are provided with upwardly extending diverging arms 4', 4'', projecting toward the upper corners of the beam 2 with their intermediate portions passing beneath the bar 3.

A locking clip 5 is associated with each shearing member for holding the same to the bar 3. As illustrated herein, the clip consists of a sheet metal plate having a slot 6 in the intermediate portion of the same to allow the arms of the shearing members to pass therethrough, and which slot may, if so desired, be sub-divided by cross-bars 7 to present additional interlocking abutments.

In the embodiment of the invention shown in Figs. 1 and 2, the arms of the shearing member are twisted; the lower portions thereof bearing against the adjacent edges of the slot 6 and the cross-bars 7 to thereby prevent relative movement of the shearing member and clip, and the additional twists or spirals acting to prevent movement of the shearing member in the cementitious body. In lieu of the twists in the shearing member for locking the same and clip against relative movement, the arms of said member may be bent as indicated in Fig. 5 to provide abutments 8 which coact with the walls of the slot 6 of the clip.

In assembling the parts of the re-inforcing structure, the shearing member is first passed beneath the bar 3, and then the clip 5, while in a flat condition, is passed down over the arms of said member as indicated in Fig. 3. The clip is then bent around the rod by means of a hammer or other suitable tool, after which the arms of the member 4 are preferably either twisted as shown in Figs. 1 and 2, or bent as shown in Fig. 5, to interlock with the clip. This method of assembling the parts is such as to permit of the assembling operation being readily and conveniently effected at the place of use, as at a building under construction, which fact is most important in that it facilitates the shipping and handling of the different parts. When the cementitious material is mold-

ed about the re-inforcing structure thus formed, said material enters the slot in the upper part of the clip and becomes keyed between the opposing walls of the same and the 5 walls of the spiral ribs of the bar 3 and operates to further lock the clip and associated shearing member in fixed connection with the bar. When the slot in the clip is subdivided by cross-bars 7, the walls of the latter 10 also co-act with the cementitious material for holding the clip against movement.

What I claim is:

1. A re-inforcing structure for cementitious bodies comprising a main bar, a shearing member partially embracing said bar and projecting laterally therefrom, and a locking clip passing about the bar to embrace the same from opposite sides thereof with the bar-embracing-portion of the shearing member held therebetween and having an opening through which the shearing member extends.

2. A re-inforcing structure for cementitious bodies comprising a generally round main bar, a shearing member partially embracing said bar and projecting laterally therefrom, and a locking clip passing about the bar to embrace the same from opposite sides thereof with the bar-embracing-portion of the shearing member held therebetween and having an opening through which the shearing member extends.

3. A re-inforcing structure for cementitious bodies comprising a main bar, a shearing member partially embracing said bar and projecting laterally therefrom, and a locking clip passing about the bar to embrace the same from opposite sides thereof with the bar-embracing-portion of the shearing member held therebetween and having an opening through which the shearing member extends; said clip and shearing member having engaging abutments for locking the same against relative movement.

4. A re-inforcing structure for cementitious bodies comprising a main bar, a shearing member projecting laterally from said bar, and a locking clip securing said member to the bar; said bar having a transverse projection which co-operates with the clip to form a locking recess for interposed cementitious material to lock the clip against movement longitudinally of the bar.

5. A re-inforcing structure for cementitious bodies comprising a main bar having a ribbed surface, a shearing member projecting laterally from said bar, and a locking clip securing said member to the bar and having an opening therein opposite the ribbed surface of the bar; the walls of said opening and the adjacent surfaces of the bar providing opposing walls for co-operation with interposed cementitious material to lock the clip and associated shearing member against movement lengthwise of the bar.

6. A re-inforcing structure for cementitious bodies comprising a main bar, a shearing member having arms projecting laterally from said bar, and a locking clip securing said member to the bar and having an opening through which the arms of the shearing member extend, the said opening being extended centrally between the arms of the shearing member and in a position opposite the bar to receive cementitious material 75 therein, for the purpose set forth.

7. A re-inforcing structure for cementitious bodies comprising a main bar having a spirally ribbed surface, a shearing member projecting from said bar, and a locking clip 80 securing said member to the bar and having an opening therein opposite the spirally ribbed surface of the bar, for the purpose set forth.

8. A re-inforcing structure for cementitious bodies comprising a main bar, a shearing member partially embracing said bar at the under side thereof and having two arms projecting laterally therefrom, and a locking clip passing about the bar to embrace the 90 same at the upper and under sides thereof with the bar-embracing-portion of the shearing member held therebetween and having an opening through which the said two arms of the shearing member extend.

9. A re-inforcing structure for cementitious bodies comprising a main bar, a shearing member partially embracing said bar and projecting laterally therefrom, and a locking clip securing the shearing member to the 100 bar; said shearing member having a spiral form providing an abutment for engaging the clip and locking the same against relative movement.

10. A re-inforcing structure for cementitious bodies comprising a main bar, a shearing member embracing said bar and having two arms projecting laterally therefrom, and a locking clip embracing the bar and having passages through which the arms of the 110 shearing member pass, the said shearing member arms being provided with abutments adjacent to the clip and co-operating therewith to lock the parts against relative movement.

11. The combination with a cementitious body, of a metallic re-inforcing structure embedded therein comprising a main bar having peripheral shoulders, a shearing member disposed transversely of said bar, and a locking member securing the shearing member to the bar and having an opening therein with its walls substantially opposed to the peripheral shoulders of the bar, the said substantially opposed walls co-operating with cementitious material entering the opening and locking the clip with the associated shearing member from movement lengthwise of the bar.

12. The combination with a cementitious

body, of a metallic re-inforcing structure embedded therein, the said structure comprising a main bar having a ribbed surface, a shearing member partially embracing said bar and projecting laterally therefrom, and a locking clip securing said member to the bar and having an opening therein opposite the ribbed surface of the bar, the cementitious material entering said opening and engaging

with the walls thereof and with the ribbed surface of the bar, for the purpose set forth.

Signed at New York, in the county of New York, and State of New York, this 12th day of July, A. D. 1906.

EDWARD F. CRANE.
